19, 1952, Serial No. 277,431

3 Claims. (Cl. 198—37)

1

This invention relates generally to control devices for a moving mechanism, and particularly pertains to a control for article conveyers employed in vending machines similar to that disclosed in my co-pending application Serial Number 225,737, filed May 11, 1951, for Vending Machine, and forms a divisional case thereof and especially concerns a weight-responsive control switch adapted to either facilitate or prevent the operation of a conveyer when the device is either subjected to the weight of an article or when freed thereof, respectively.

One of the objects of this invention is the provision of a simple, relatively inexpensive and highly effective weight-responsive switch having an actuating member which is placed in the path of articles propelled or carried by a conveyer, so that when an article becomes positioned over the actuating member, the weight of the article will cause the latter to close the switch, thus closing an electric control circuit, whereby the conveyer-actuating means are released into operative position.

Another object of this invention is the provision of a weight-responsive control switch composed of a switch unit and of an actuating member for the latter, and wherein the switch unit comprises at least two superimposed resilient blades carrying contacts and which blades are normally separated, said switch-actuating member comprising a pivotally supported frame having projecting ribs or flanges intended to be engaged by and depressed by an article, and an extension forming a part of the frame, said extension being adapted to be normally supported by one of the blades of the switch, thereby elevating the frame so that its ribs or flanges project into the path of moving articles, and which extension is designed to depress the switch blade supporting it when an article assumes a position above the ribs or flanges extending from the frame.

The foregoing and numerous other objects and advantages of the present invention will become more fully apparent from the ensuing description of the accompanying drawings, which latter form a part of the present disclosure and in which:

Fig. 1 is a plan view of an article-supporting platform equipped with an endless conveyer for propelling articles, and which platform operatively supports a weight-responsive switch in accordance with the present invention.

Fig. 2 is a vertical cross section through two superimposed platforms equipped with weight-responsive control switches, said section being taken approximately along lines 2—2 of Fig. 1.

2

Fig. 3 is a section taken approximately along lines 3—3 of Fig. 2.

Fig. 4 is a fragmental top view of the frame structure of the switch actuating member.

5 Fig. 5 is a section taken along lines 5—5 of Fig. 4.

Fig. 6 is a perspective view of the switch-actuating member, and

10 Fig. 7 is a wiring diagram denoting the major electric elements employed in the operation of article conveyers for vending machines, including the weight-responsive switch, the subject of the present disclosure.

In Figures 1 to 5 numeral 10 denotes a platform such as may be employed in a vending machine and in which platform is provided a guide channel 11 (see Fig. 1) in which operates an endless conveyer 12 having a plurality of article retainers 13 supported by and extending from the exterior 15 edges of interconnected chain links 14. At the interior edge of the links are provided recesses 15 which are adapted to be successively engaged by a conveyer-actuating lever 16 which is operated by means of lever 17 and shaft 18, the latter being 20 swung in an arc by means of a linkage 19 driven by motor 20. Driven also by the motor is a cam 21 which is adapted to operate a switch-closing lever 22 hinged at 23 (see Fig. 7), the purpose of which will be explained presently.

25 Controlling the operation of motor 20 is a three-blade switch 24 composed of a central long blade 25 and an upper short blade 26 and a lower short blade 27. The middle blade 25 has two adjacent contacts, whereas the outer blades 26 and 30 27 carry one contact each. The upper contact of blade 25 and the contact of blade 26 are normally closed as shown in Figs. 1 and 7.

35 The operation of the conveyer is predicated upon the closing of an electric circuit controlled by the closing of four independent switches, one of them being located in coin mechanism 28 (see Fig. 7), but is not illustrated. That switch is closed when a coin of the required denomination passes through that mechanism. Triple blade 40 switch 24 represents another of the four switches and is operated by means of arm 29 extending from a vertical shaft 30 from which latter also projects a lever 31 engaged by pin 32 (Fig. 1) extending from a spring-loaded lever 33. The latter bears against the top of hook-shaped end 34 of chain-actuating lever 16, and from that hook-shaped end extends a pin 35 adapted to move chain detent 36 out of engagement with the recess 15 of one of the links engaged by the detent, as will be explained presently.

Spring 33' forces lever 33 to tensionally engage

hook end 34, and also causes pin 32 of the lever to press against lever 31. Detent 36 is urged towards the chain by spring 35, as is actuating lever 16 by the action of lever 33.

Mounted above lever 16 is a solenoid 37 provided with a vertically movable armature 38, which latter is adapted, when the solenoid is de-energized, to drop toward platform 10 and, at a certain position of lever 16, in the latter's path of operation, in the manner indicated in Fig. 1. When the solenoid is energized, its armature 38 is elevated and clears lever 16, and releases it to move into engagement with the chain for eventually engaging one of the link recesses 15, that movement of lever 16 being effected by the spring-loaded lever 33. At the same time switch-arm operating lever 31, engaged by pin 32 of lever 33, is swung in downward or anti-clockwise direction, whereby switch-operating arm 29 is also caused to move in that direction and opens the contacts of blades 26 and 25 and closes the contacts of blades 25 and 27. By the closing of these latter contacts, motor 20 becomes energized.

Solenoid 37 becomes energized by closing push button switch 39 (see Fig. 7), representing the third switch controlling the circuit, but the closing of the solenoid circuit by push button switch 39 can be effected only when the switch of the coin mechanism, the switch blades 25 and 26 and the fourth switch, a weight-responsive switch 40 are all closed, otherwise the closing of switch 39 will not energize solenoid 37.

Weight-responsive switch 40 is composed of two devices, a switch proper 41 and an operating member 42 for that switch proper. The latter comprises two normally separated resilient contact blades of which blade 43 is longer than blade 44. Operating member 42 consists of a frame 45 and a switch-engaging arm 46 extending from the frame and forming an integral part thereof. At the end of the arm is provided a pin 47 adapted to rest upon longer blade 43 of switch 41, blade 43 being intended to resiliently support pin 47. Frame 45 is pivotally supported at 45' from platform 10 by any suitable means such as an inverted channel 48, shown in Fig. 5, which is riveted or otherwise secured as at 48' to the platform, and a pivot pin 49. The outer edges or flanges 50 of the frame as well as ribs 50' formed from the frame material project through suitable slots above the platform, as seen in Figs. 2 to 5, the frame being held in that position by pin 47 of extension 46 resting upon and being resiliently supported by upper blade 43 of switch 41.

When now an article A held in one of the retainers 13 is brought into position above the frame, its flanges 50 and ribs 50' are depressed by the weight of the article, as seen in Figs. 2 and 3, and frame 45 swings downwardly about pivot pin 49, thereby causing pin 47 of frame extension 46 to exert sufficient pressure upon blade 43 to bring it into contact with blade 44, thus closing weight-responsive switch 40. With switch 40 closed by the weight of an article, push-button switch 39 can be operated; and when thus operated, solenoid 37 becomes energized, elevates its armature 38 and releases chain-actuating lever 16 to its operative position and into engagement with chain 12.

As stated before, the release of lever 16 into its operative position is accompanied by the release of switch arm 29 which opens the normally closed contacts of blades 26 and 25 and closes the nor-

mally open contacts of blades 25 and 27 whereby motor 20 becomes energized. As the motor starts to rotate, its cam 21 will engage switch-closing lever 22 and cause it to close a quadruple blade switch 51 (see Fig. 7) composed of a pair of upper blades 52 and 53 and lower blades 54 and 55. The latter blades constitute a holding switch for the motor by means of which current is supplied to the motor when blades 25 and 27 of switch 24 become separated as actuating lever 16 reassumes its initial, inoperative position shown in full lines in Fig. 1. Switch blades 52 and 53 are intended to introduce into the field winding of the motor a resistance 56 whereby the motor speed is slowed down before it comes to a stop.

As has been explained in the aforementioned application Serial Number 225,737, chain conveyer 12 is actuated by lever 16 successively in that the hook-shaped end 34 of that lever first is released by solenoid armature 38 into a contacting position with the chain, whereupon the lever is caused to move towards detent 36 so that pin 35 at the hook-shaped end of lever 16 lifts detent 36 out of engagement from the chain, whereupon hook 34 engages the recess of the link next to that formerly engaged by detent 36. When this interengagement between lever 16 and the recess in the chain link is effected, the lever is caused to move in left hand direction and past its starting position, a position defined by the full-line position of connecting lever 17 shown in Fig. 1. As lever 16 commences its movement, solenoid 37 becomes de-energized and releases armature 38. When now lever 16 moves towards its starting position it will be caused by dropped armature 38 to assume its inoperative, full-line position shown in Fig. 1, that is, the position at which the lever clears link chain 12.

From the foregoing it will be clear that unless weight-responsive switch 40 is closed by the weight of an article propelled by the conveyer, solenoid 37 cannot be energized by closing push-button switch 39. If, on the other hand, switch 40 is closed by the weight of an article and a coin inserted in the coin mechanism 28 has caused the closing of the circuit controlled by blades 26 and 25 of switch 24, then the closing of switch 39 will produce the following effect: Solenoid 37 will become energized, whereby detent 36 will release lever 16 to assume a contacting position with chain conveyer 12, this movement being induced by spring loaded lever 33. At the same time switch arm 29 will open the contacts of blades 26 and 25 and close the contacts of blades 25 and 27, whereby the motor is energized. As the motor revolves, cam 21 will compress quadruple switch 51 for the purpose stated above.

The importance of weight-responsive switch 40 becomes readily evident when it is considered that the conveyer cannot operate unless it holds at least one article of merchandise, and unless that article is brought over the switch-actuating member to effect closing of the switch by its weight.

While only one embodiment of that switch structure is illustrated and described, its construction may be changed to adapt the same for use in connection with different conveyer or other mechanisms, for which reason any obvious changes and modifications of the switch structure are deemed to reside within the scope of the present invention as defined in the annexed claims.

5

What is claimed as new is:

1. In a weight-responsive switch device for the control of an actuating mechanism of an article conveyer, said device comprising a normally open switch and a weight-responsive member for closing the switch; said actuating mechanism being adapted to successively first engage the conveyer at a certain point and to move it for a predetermined distance and then to release the conveyer and to revert to that engaging point; electrical- 10 ly operable means in cooperation with said mechanism and controlled by said switch device and being adapted, when de-energized, to prevent said mechanism from engaging and moving the conveyer, and, when energized, to release said mechanism into a conveyer-engaging and conveyer-operating state; said weight-responsive member of the switch device being disposed in the moving path of articles propelled by the conveyer and being adapted, when subjected to 20 the weight of an article, to close the switch, whereby said electrically operated means become energized, and wherein an endless platform having a plurality of slots is provided for supporting articles propelled by the conveyer. 25

2. In a weight-responsive switch device as in claim 1, said weight-responsive member comprising a depressible frame structure pivotally

6

suspended from said platform and being provided with a plurality of ribs adapted to normally project through said platform slots, said frame structure having an extension operatively engaging said switch and being movable with said frame structure when the latter is depressed by the weight of an article brought above said ribs, thereby causing the extension to close the switch.

3. In a weight-responsive switch device as in claim 1, said weight responsive member comprising a pivotally suspended frame having upwardly projecting, spaced rib formations, normally extending through said slots above the platform, and a switch-operating lever extending from the frame and operatively engaging said switch; said frame being adapted to swing about its pivot when any one of said rib formations is subjected to the weight of an article, whereby said lever is caused to close said switch.
